UNITED STATES PATENT OFFICE.

CLAIBORN CLARK, OF LOS ANGELES, CALIFORNIA.

EAR DEVICE FOR DEAF.

1,408,500.

Specification of Letters Patent. Patented Mar. 7, 1922.

Application filed May 26, 1919. Serial No. 299,933.

To all whom it may concern:

Be it known that I, CLAIBORN CLARK, a citizen of the United States, residing at Los Angeles, in the county of Los Angeles,

5 State of California, have invented new and useful Improvements in Ear Devices for Deaf, of which the following is a specification.

The present invention relates to improvements in ear devices for the deaf, and it is an object of the invention to provide an extremely simple and effective device that will greatly assist people who are afflicted with deafness.

15 The present invention provides a device that may be comfortably worn in the ear and which greatly assists the wearer to hear. The invention embodies a tubular sound receiver in which is mounted 20 a vibrator or tongue. The sound receiver is substantially a cone shaped tube and is so shaped that it may be easily and comfortably carried in the outer passage way of the ear. The tongue is a sensitive 25 thin metal member which extends diametrically across the inside of the sound receiver. The tongue is attached to the sound receiver at the outer or large end and extends freely inwardly through the receiver 30 to or near the small end. The tongue acts as a division wall, as it divides the interior of the receiver into two parts. The shape of the tongue conforms with the shape of the inside of the receiver, that is, the edges 35 of the tongue are parallel to the inside wall of the receiver. The tongue being of thin sensitive metal and shaped as just described, is caused to vibrate by faint sounds. When the device is in the ear sound waves easily 40 enter the large end of the receiver and the interior shape of the receiver is such as to concentrate them and cause the tongue to effectively vibrate. An opening in the small 45 end of the receiver forms a passage way through which the sound, which is caught by the receiver and intensified by the vibrator, may readily pass and act upon the inner organs of the ear. The details of construction of the invention and further 50 features of it will be readily understood from the following detailed description of a specific preferred form of the invention throughout which reference is had to the accompanying drawings, in which—

55 Fig. 1 is a side elevation of the device; Fig. 2 is a plan or top view of the device taken as indicated by line 2—2 on Fig. 1;

Fig. 3 is a sectional view through the device taken as indicated by line 3—3 on Fig. 2; and Fig. 4 shows a side elevation of a 60 modified form of the device.

In the drawings the numeral 10 designates the tubular conical sound receiver or cup, and numeral 11 designates the diaphragm or tongue which is mounted therein. The cup 10 is shaped as clearly shown in Fig. 3, the configuration of its outer surface conforms very closely with that of a truncated cone. And the inner surface is substantially the same with the exception 70 of a slight shoulder 13 near the outer or larger opening. The small end of the cup 10 is preferably slightly curved as clearly shown in Figs. 1 and 3, so as to fit the curvature of the passage way to the inner organs 75 of the ear. This slight crooked or curved portion 10^a also tends to prevent the device from working or falling out of the ear. The cup shaped portion is preferably made of a metal that will not readily tarnish, discolor or corrode or injure the ear. It may be found satisfactory, to make the cup out of brass or the like and plate it with such a metal as nickel. In order to make the device light and thereby prevent it from annoying or bothering the user, the cup may be made of a light metal or alloy that has the general characteristics hereinabove 80 stated. On the inner surface of the cup a short distance from the edge 12 of the outer 90 or large end there is a slight shoulder 13, as is clearly shown in Fig. 3. The shoulder is rounded off in such a manner as to prevent it from hindering the sound from entering the cup. The wall portion 14 of 95 the inner surface of cup 10, between the edge 12 of the large opening and the shoulder 13, is straight and has no curve or taper, the reason for which will hereinafter be described.

100 The tongue 11 is firmly held at the outer or large end of the cup. The tongue has a broad portion 15 which extends diametrically across the cup and engages the wall 14 of the inside of the cup. The portion 105 15 of the tongue has parallel sides 15 which are made to fit tightly against the wall 14. This mounting of the tongue 11 in the cup 10 is sufficiently tight to allow the tongue to be used as a handle by which the device 110 may be placed in or withdrawn from the ear; and is also tight enough to prevent any possibility of it becoming disengaged if the device is dropped or subjected to a sud-

den blow or pressure of any kind. The tapering tip 17 of the tongue extends down into the cup and its sides 18 are parallel to but do not touch the inner wall 19 of the 5 cup. As shown in the drawings, the tip 17 preferably does not extend into the curved portion 10^a of the cup 10. The tip of the tongue is preferably made broad enough to substantially extend entirely across the cup 10 leaving only a slight clearance between the sides 18 and the wall 19. The tongue member is made of thin resilient metal that will be vibrated by ordinary sounds. For instance, I find that a tongue made of hard 15 brass about $\frac{1}{2}$ " thick will resonate effectively to ordinary sounds. It may be desirable to make the tongue out of a material that has the same characteristics as the material out of which the cup is made, that is, a material 20 that will not corrode or become easily discolored. The tongue must also be a durable metal and must be flexible enough to allow it to properly vibrate.

The entire device should be well finished 25 and all the surfaces should be perfectly smooth. The reason for having the outer surfaces smooth is to prevent scratching or injuring the ear, while the reason for having the inner surfaces smooth is to prevent the 30 sound from being deadened. As will be clearly seen in the drawings, the device does not restrict in any way the passage way 35 into the ear but allows the sound to readily pass through it. In the drawings I have shown a cover 20 that may be slipped over the sound receiver to prevent it from coming in contact with the skin. The cover 20 may be made of rubber or the like and covers 40 may be made of various thicknesses so that the device may be made to fit the ear by using a cover of the proper thickness. By making the cover of rubber it is very easily 45 slipped over or taken off of the receiver.

The general proportions and shape of the 50 device may be varied without departing from the invention, for instance, a modified form of device is shown in Fig. 4. The form of device shown in Fig. 4 is similar to the preferred form shown in the other 55 figures except that it has not the curved portion 10^a at the small end. A device of this kind may be used in a case where the passage way into the ear is disformed or restricted in such a way as to make it impossible or inconvenient to use the preferred 60 form of device.

Having described a preferred form of my invention, I claim:

1. In a device of the character described,

a tapered cylindrical receiver and a tongue 60 in said receiver, said tongue being attached to said receiver at one end only and extending freely longitudinally into said receiver, and forming a partition across its interior without touching the receiver wall. 65

2. In a device of the character described, a tapered cylindrical receiver and a tongue in said receiver, said tongue being attached to said receiver at the large end only and extending freely longitudinally into said receiver toward the small end and forming 70 a partition across its interior without touching the receiver wall.

3. In a device of the character described, a tapered cylindrical receiver having a 75 shoulder on the inner surface near the large end and a straight portion between the shoulder and the large end, and a metallic tongue in said receiver, said tongue extending diametrically across said receiver and 80 having a portion adapted to engage the straight portion of said receiver and the rest of said tongue projecting into the tapered receiver and being formed so as to extend across the interior of said tapered receiver 85 as a partition but not to come in contact with the interior wall of the receiver; so that the projecting part of the tongue is free to vibrate.

4. In a device of the character described, 90 a conical receiver open at both ends and a vibrator mounted therein, said vibrator consisting of a tapered flat tongue secured across the interior of the receiver at its larger end, the smaller end extending longitudinally into the smaller end of the receiver and spaced therefrom to be free to vibrate and forming a partition across the receiver interior.

5. In a device of the character described, 100 a tubular receiver adapted to be placed in sound conveying relation to the ear, and a vibratory partition in said receiver comprising a tongue extending lengthwise of the receiver and extending transversely across 105 it to divide its interior, the tongue being mounted in the receiver at one end only and having its other end projecting freely longitudinally of the receiver with its edges close to but not touching the receiver wall 110 to form a vibratory partition.

In witness that I claim the foregoing I have hereunto subscribed my name this 14th day of May, 1919.

CLAIBORN CLARK.
